UNITED STATES PATENT OFFICE.

JOHN H. CRATTY AND HARRY W. NEWELL, OF SPRINGFIELD, MASSACHUSETTS.

AUXILIARY AIR DEVICE.

1,148,830.

Specification of Letters Patent.

Patented Aug. 3, 1915.

Application filed October 6, 1913. Serial No. 793,569.

To all whom it may concern:

Be it known that we, JOHN H. CRATTY and HARRY W. NEWELL, both citizens of the United States of America, and residents of 5 Springfield, in the county of Hampden and State of Massachusetts, have invented a new and useful Auxiliary Air Device, of which the following is a specification.

Our invention relates to improvements in 10 air appliances used in connection with carburetors on gasoline engines and the like, and in its general aspect consists of an air chamber mounted on a conduit which is adapted to be attached to and open into the 15 intake which leads from the carburetor to the manifold of a hydrocarbon-burning engine, a valve for the admission of air to such chamber, and means to regulate or limit the movement of said valve, all as herein- 20 after set forth.

The object of our invention is to provide an engine of the type noted above with a simple but entirely practicable and efficient device for supplying with auxiliary air the 25 fuel mixture from the carburetor on its way to the manifold of such engine, to the end that the engine develops more power with less fuel, is rendered more flexible and caused to run more steadily, and is kept cooler, and 30 the carburetor does not need to be adjusted so frequently.

Other objects will appear in the course of the following description.

We attain the objects and secure the advantages of our invention by the means 35 illustrated in the accompanying drawings, in which—

Figure 1 is an end elevation of a device 40 which embodies a practical form of our invention, and shows the application of the same, and, Fig. 2, a longitudinal section through said device and a portion of an intake pipe to which it is attached.

In the first view the valve is shown open 45 in full lines and closed by dotted lines.

Similar figures refer to similar parts throughout the several views.

In the first view we show a carburetor at 1 50 with a conduit or pipe, which is termed an intake, at 2, and a portion in section of this pipe or intake appears in the second view. The fuel from the carburetor 1 passes on its way to the manifold, which latter is not

herein represented, through the intake 2, and it has been demonstrated that the action 55 and efficiency of the engine is greatly improved and enhanced by introducing into said fuel a quantity of outside air before said fuel leaves said intake.

We will now proceed to describe in detail 60 the device by means of which the auxiliary air is introduced into the intake 2 and the fuel therein, it being first observed that the amount or quantity of such air must be regulated and controlled in order to produce 65 the desired results.

Tapped into or otherwise attached to the intake 2 so as to open into the same is a horizontal pipe 3, and mounted on the outer end of such pipe and opening into the same at 70 one end is a casing 4 which forms or constitutes an air chamber.

Rotatably mounted on a hub 5 at the outer end of the casing 4 is a disk valve 6 which has an opening or port 7 therein. There is 75 an opening or port 8, in the outer end wall of the casing 4, into alignment with which the port 7 in whole or in part may be brought. Projecting from the rim of the valve 6, at diametrically opposite points, are 80 two arms 9 and 10.

A spring 11 has one end attached to the arm 9 and the other end attached to some fixed point (not shown) on the engine. The purpose of the spring 11 is to maintain the 85 valve 6 in its closed position, that is, with the port 7 out of registry with the port 8, and to return said valve to such position.

Attached at one end to the arm 10 is an operating rod 12 for the valve, by means of 90 which said valve is partially rotated, against the resiliency of the spring 11, and actuated into open position or with the port 7 in registry with the port 8. The rod 12 or some connection therewith extends to the operating point, which in an automobile would be 95 the steering-post.

In order to permit the valve 6 from moving too readily on the hub 5, we provide a tension spring 13 and a regulating screw 14, 100 the latter being tapped into the hub 5 and the outer end of the casing 4. The spring 13 is introduced between the head of the screw 14 and the valve 6, and so presses on said valve and prevents the same from rattling 105 or moving except when actuated by the rod

12 or the spring 11. The amount of pressure exerted by the spring 13 on the valve 6 may be increased or decreased by turning the screw 14 in or out.

5 Some provision is necessary to limit the movement of the valve 6, especially in opening, and such provision must comprise means of the adjustable type, because a greater supply of auxiliary air is required for an 10 engine of large capacity than for one of small capacity, hence the port 8 must be opened wider in some cases than in others. Atmospheric conditions, also, may require different adjustments of the valve 6. Thus 15 it is apparent that the adjustment of said valve should have a wide range, otherwise the device would not be suitable for all kinds and sizes of engines, and capable of advantageous use under most if not all atmospheric variations. For this purpose we 20 provide a stop 15 in the form of an incomplete ring or band which fits the outside of the casing 4 just inside of the valve arms 9 and 10, where it is held by means of a screw 25 16 tapped into said stop to engage said casing, and has at the ends which are somewhat remote from each other outwardly projecting lugs 17 and 18. The parts are so arranged that the arm 10 is between and operates 30 between the lugs 17 and 18. The lug 17 receives the arm 10, when the valve 6 closes, and so limits the closing movement of said valve, while the lug 18 receives said arm, when said valve is opened, and so limits the 35 opening movement thereof. By readjusting the stop 15 so as to locate the lug 18 farther to the left, the extent to which the port 8 is opened, when the valve 6 is actuated to bring the arm 10 into contact with said lug, is decreased, since said arm sooner comes into 40 contact with said lug, and by readjusting said stop so as to locate said lug farther to the right, the extent to which said port is opened, when said valve is actuated to bring 45 said arm into contact with said lug, is increased, since said arm later comes into contact with said lug. The screw 16 renders such adjustment easy of accomplishment, as will be readily understood.

50 In practice, the stop 15 is first adjusted in such a manner as to permit the valve 6 to be opened to whatever extent may be necessary to admit the proper amount of air to the intake 2 by way of the ports 7 and 8, and casing 4, and the tube 3, when the device is ready for use. The operation simply consists in actuating the valve 6 to open it as far as the lug 18 will permit, whenever additional air is required for the fuel mixture, 55 and to release said valve to the closing action of the spring 11 when it is desired to cut off the extra supply of air. In closing the valve 6 is brought to a stop when the arm 10 contacts with the lug 17.

It will be observed that the size or diameter of the casing 4 is considerably larger than that of the tube 3. This is an important structural feature, because very much better results are obtained when the auxiliary air is first received in a comparatively large chamber and then discharged or drawn into the intake through a comparatively small conduit, than would be possible if such air passed directly through a conduit of uniform size from the point where the air first enters to that where it discharges into the intake. In the latter case there would be a great liability that too much auxiliary air would be sucked into the intake with so much abruptness or velocity that it would fail to commingle thoroughly with the fuel mixture. With the present construction is experienced no difficulty of this kind.

85 In opening the valve sufficient force is required to overcome what little resistance the spring 13 may offer to this action in addition to the resistance of the spring 11, and the latter must be strong enough to overcome the resistance of said spring 13 to the closing operation, or to the action of said spring 11 in closing said valve.

90 More or less change or modification in the construction and arrangement of some or all of the parts and members of this device, as herein shown and described, may be made, without departing from the nature of our invention.

95 What we claim as our invention, and desire to secure by Letters Patent, is—

1. The combination, in an auxiliary air device, with a tube adapted to be connected with a fuel pipe, a casing of larger diameter mounted on said tube and opening into the same, said casing having an inlet port in one end thereof and provided with a hub at such end, and a spring-actuated rotatable valve disk mounted on said casing and hub and having a port which is capable of being brought into registry with said first-mentioned port, said disk being provided with an arm, of an incomplete band adjustably mounted on said casing and provided with lugs at the ends which extend into the path of said arm, and a set-screw to hold said band in place.

105 2. The combination, in an auxiliary air device, of a tube adapted to be connected with a fuel pipe, a casing of larger diameter mounted on said tube and opening into the same, said casing having an inlet port in one end thereof and provided with a hub at such end, a spring-actuated rotatable valve disk mounted on said casing and hub and having a port which is capable of being brought 110 into registry with said first-mentioned port, said disk being provided with an arm, a

regulating screw tapped into said hub, said screw having a head, a spring arranged between said disk and the head of said screw to bear against and frictionally engage said 5 disk, an incomplete band adjustably mounted on said casing and provided with lugs at the ends which extend into the path of said

arm, and a set-screw to hold said band in place.
